UNITED STATES PATENT OFFICE.

CHARLES G. C. WHYTE, OF MARRICKVILLE, SYDNEY, AND ARTHUR RAU, OF ST. PETERS, SYDNEY, NEW SOUTH WALES, AUSTRALIA; SAID RAU ASSIGNOR TO SAID WHYTE.

MANIFOLDING COPYING-BOOK.

942,023.

Specification of Letters Patent. Patented Nov. 30, 1909.

Application filed July 8, 1908. Serial No. 442,558.

To all whom it may concern:

Be it known that we, CHARLES G. C. WHYTE, a citizen of the Commonwealth of Australia, residing at Pile street, Marrickville, Sydney, in the State of New South Wales, Commonwealth of Australia, accountant, and ARTHUR RAU, a citizen of the Commonwealth of Australia, residing at No. 53 Terry street, St. Peters, Sydney 10 aforesaid, professional shorthand writer, have invented certain new and useful Improvements in and Relating to Manifold Copying-Books; and we do hereby declare the following to be a full, clear, and exact 15 description of the invention, such as will enable others skilled in the art to which it appertains to make and use the same.

By means of this invention provision is made to further increase the number of 20 produced copies of written matter in books hitherto serviceable either for duplicating or triplicating purposes, in which the well known method is adopted of using, in combination with the leaves, an interleaved 25 transfer or copying sheet, whose withdrawal will allow of the combined sheets being detached, while the copying medium is available for further use. Such books have been in use for recording "counter sales", "orders 30 out", "accounts", "correspondence", and the like.

By our improved devices hereinafter described with the aid of double faced transfer paper, used either singly or folded, in 35 association with a separate packet of transparent sheets, the number of copies may be increased from two to three, or from two to five, as may be required. This is accomplished by using conjointly the covers of 40 the book, and attaching to their inner surfaces two sets or packets of leaves, so placed in juxtaposition that they will, when the book is closed, be in contact with each other, one set being composed of transparent sheets 45 only, and the other of opaque sheets only, or of opaque sheets (single or folded) in combination with single transparent sheets.

Referring to the drawings which form part of this specification: Figure 1 represents an ordinary duplicating book. Fig. 2 shows covers of a book made suitable for the application of this invention, with index in position on the back cover. Fig. 3 represents 50 a packet of transparent sheets suitable for

attachment to a cover as in Fig. 2. Fig. 4 represents a packet of opaque folded sheets as at present in use, fitted with combined clips and hinges for attachment to a cover as in Fig. 2. Fig. 5 represents a packet of combined transparent and single opaque 60 sheets, prepared for attachment to a cover as in Fig. 2, serviceable with a folded transfer sheet to produce additional copies. Fig. 6 shows the covers as in Fig. 2 combined with packets of leaves as in Figs. 3 and 4. 65 Fig. 7 shows the covers as in Fig. 2 combined with packets of leaves as in Figs. 3 and 5. Fig. 8 is an edge view of a closed book, showing packets overlying. Fig. 9 shows the hinged packet folded over the 70 transparent packet, to give access to the index. Fig. 10 is a detail of a combined packet clip and eyelet, also serviceable for attachment to the cover. Fig. 11 is a detail of 75 staple for attachment to covers to receive eyelet, also serviceable for attachment to the packet. Fig. 12 shows the method of detaching transparent and folding leaves combined.

The back and front book covers, A and B, 80 are joined by the flexible piece C, which is made of a width to correspond to the combined thickness of the packets D and E, which need not necessarily be of the same thickness because the materials of the two 85 are different. The packet D is composed of ordinary paper sheets, or of such interleaved with transparent sheets or tracing paper interspersed in any desired order and serviceable either as single or folded sheets 90 as may be arranged, to accord with the use of a single piece of double faced copying paper F, which may be bound up with the packet D, or left loose, or to accord with a folded piece of double faced copying paper 95 F F. The packet E is made up wholly of sheets of transparent paper, or tracing paper, lightly secured at the edges E¹ so as to be easily separated. It is intended that these packets shall be secured to their respective 100 covers, so that when the book is opened for use each set will occupy a position distinct from the other, thus either or both sets may be utilized when desired.

The sheets or leaves of packet D are made 105 detachable by lines of perforations D² placed near the binding edge, so that as each sheet is removed a stub D¹ remains. While

the stock of leaves is being exhausted, the thickness of the stub will remain the same. Duplicate books with leaves so constructed are at present provided with devices to retain the stubs in position until the complete exhaustion of the packet, but no provision is made in them for overturning the packet to enable the cover to which it is attached to be exposed to view on the inside, therefore this invention is devised to allow of this being done, because it is essential that the salesman's index G shall be removed from cover B, Fig. 1, and transferred to the inside of cover A, Fig. 2, the slit parts A¹ formed in the binding used for the purpose. This index, which is used by the salesman for recording the amount of each sale, is used as frequently as the packet D which overlies it, and in whose leaves the duplicate, triplicate, or multiplicate records are to be made. Ordinarily such leaves are bound in packets with wire fastenings piercing the stub portion D¹, and are rigidly held against the surface of the cover by clips and backing pieces.

To render the packet removable a new form of combined staple and eyelet H and combined hook or lug and staple H¹ (Figs. 10 and 11) are provided, to be used in association with the packet D and the cover A. Both devices act as clips or binders by piercing the material and clenching the ends over the surfaces. Three of the combined clips and eyelets H are shown attached to the stubs D¹ in Figs. 4 and 7, and a similar number of combined clips and staples H¹ are fixed to the cover A, Figs. 2, 6, and 7. The eyelets H preferably lie at the surface level of the stub D¹, as indicated in Figs. 8 and 9. Each hook H¹ is passed through the corresponding eye H, as shown in Fig. 9, but may be readily separated therefrom at will. In said figures the transfer sheet is shown in dotted lines.

In Fig. 9 the packet D is shown overlying the packet of transparent sheets E which rests on the cover B, thus allowing free access to the index G, the staples H¹ standing at a sufficient height to allow of a free movement of eyelets H, and wholly avoiding any movement of the cover A, which is allowed to lie flat for writing purposes. The flexible part C readily accommodates itself to the changed position of the packet D, which, when thus positioned, has its perforated line D² coinciding approximately with the edges E¹ of packet E. This packet is held in position against the cover B by the bottom tongues E² inserted in the slits B¹ formed in the cover B, which prevents the packet from being displaced. As an additional precaution against the separation of the leaves forming the packet E, they are held at the corners in housings B² formed of stiffened covering material having sufficient spring

to engage with the corners of the packet as its thickness diminishes. The individual leaves of packet E may be separated therefrom successively and transferred to the packet D. A single leaf is thus used with the latter when a single sheet of transfer paper F is available. Two such leaves are thus transferred when a folded sheet F of transfer paper is used.

The packet of transparent leaves remaining in its position upon cover B, may be folded over, as in Fig. 8, without fear of disarrangement; and it is intended that while the stock of opaque, or combined opaque and transparent, leaves is removed, what remains of the packet E shall fall into the space created by the removal of the leaves of packet D, taking a position against the stub D¹, and allowing the covers of the book to be closed in a proper manner, the flexible piece C accommodating itself to this arrangement.

It is to be understood that while the combined clip and eyelet H and the combined clip and staple H¹ are shown attached to the stub D¹ and the cover A respectively, the order of attachment may be reversed, in which case the configuration of the respective devices would be as shown dotted in Figs. 10 and 11, the object being to place the eyelet in a vertical position when attached to the cover A, and the staple in a horizontal position when attached to the stub D¹. Either of these devices, when attached to the cover, will not need renewal, but as each stub is removed the fresh packet would have its own attachments to engage with the permanent parts on the cover.

In Figs. 4 and 6, the double-sided transfer sheet F is shown secured to the stub D¹, to be overlaid upon the lower portion of the folded opaque sheet D. The transparent sheet taken from packet E would be laid thereon, and be kept in position by the upper portion of the folded opaque sheet D, upon which the original writing would be made, as at present. The writing, of course, would be visible through the transparent sheet. Where the folded double sided transfer sheet is used, and the transparent sheets are interleaved in the same position as for the single transfer sheet, a further set of copies would be produced.

By the combination of two separate sets or packets of leaves in the same book, provision is made either for producing a series of duplicate copies and a series of triplicate copies, or a series of triplicate copies only, or, they may be taken alternately in duplicate and triplicate, but the discontinuance of the taking of triplicate copies would not result in the loss of the transparent sheets, which are still held in reserve for use when required.

In Fig. 12 a triplication of writing is

shown effected with a transparent sheet removed from the packet E, the loose sheet and the folding sheet being removed simultaneously, the single transfer sheet F falling naturally into position upon the packet E.

In this invention it is not sought to claim simply a duplicator, multiplicator, or manifold book, but

Having now described our invention, what we claim as new, and desire to secure by Letters Patent is:—

1. A manifolding book consisting of two covers and a flexible back and a packet of paper fastened to one of said covers by means of eyes which pass through said packet and hooks fastened to said cover and engaging said eyes.

2. In combination with a pair of book covers and their connecting back a series of staples attached to one of said covers, a detachable packet of leaves of paper and a series of staples engaging said packet, the staples of one set being provided with eyes and the staples of the other set being provided with hooks, which removably engage said eyes, substantially as set forth.

3. In a manifolding book, a suitable cover, a packet of paper in combination with means for fastening the same to one leaf of said cover said means passing through said packet and provided with eyes and hooks attached to said leaf of said cover said eyes engaging said hooks.

4. In a manifolding book, consisting of a cover, a packet of transparent paper, another packet of paper consisting of transparent and non-transparent paper, and a flexible back joining said covers, said last mentioned packet being provided with eyes

40 having necks, and staples extending from said necks, said staples passing through and clenching on the other side of said packet, and hooks provided with necks and passing through and clenching on the other side of

the said last mentioned cover; said eyes engaging said hooks.

5. A manifolding book consisting of a cover, a packet of paper attached to one leaf thereof, means for attaching said packet to the said leaf, said means consisting of eyes secured to the said packet and hooks attached to the said cover, and a flexible back for the said book.

6. A manifolding book consisting of a cover, a packet of paper, and means for fastening said packet of paper to said cover, said means consisting of eyes fastened to the said packet and hooks attached to the said leaf of said book, said hooks being all turned in the same direction.

7. In manifolding books the combination of a cover and a packet of paper secured to one leaf of said cover by means of corner caps and slits, with another packet attached to the other leaf of said cover, staples passing through said last mentioned packet of paper and hooks attached to the said last mentioned leaf of said cover, said eyes engaging said hooks, and a flexible back joining the leaves of said cover.

8. A manifolding book consisting of a cover, a packet of writing material flatly secured to one leaf of said cover, another packet of writing material revolvably mounted upon the other leaf of said cover, eyes fastened to said last mentioned packet and hooks fastened to the last mentioned leaf of the cover, said eyes engaging said hooks, and means for slidably mounting an index upon the said last mentioned leaf of said cover.

In testimony whereof we have signed our names to this specification in the presence of two subscribing witnesses.

CHARLES G. C. WHYTE.
ARTHUR RAU.
